Primary Examiner — George A Bugg*Assistant Examiner* — Jeremy S. Swartz(74) Attorney, Agent, or Firm — Tarter Krinsky & Drogin LLP(57) CLAIM

The ornamental design for a bag dispenser as shown and described.

DESCRIPTION

FIG. 1 is a front perspective view of the bag dispenser showing the present design.

FIG. 2 is a front view thereof.

FIG. 3 is a rear view thereof.

FIG. 4 is a left view thereof.

FIG. 5 is a right view thereof.

FIG. 6 is a top view thereof; and,

FIG. 7 is a bottom view thereof.

The broken lines shown in the drawings are for the purpose of showing portions of the bag dispenser and form no part of the claimed design.

1 Claim, 5 Drawing Sheets(56)
